UNITED STATES PATENT OFFICE.

GEORGE C. WORTHINGTON, OF ELYRIA, OHIO, ASSIGNOR TO THE WORTHINGTON BALL COMPANY, OF ELYRIA, OHIO, A CORPORATION OF OHIO.

DESIGN FOR A PLAYING-BALL.

45,734.

Specification for Design.

Patented May 5, 1914.

Application filed January 22, 1914. Serial No. 813,806. Term of patent 7 years.

To all whom it may concern:

Be it known that I, GEORGE C. WORTHINGTON, a citizen of the United States, residing at Elyria, in the county of Lorain and State of Ohio, have invented a new, original, and ornamental Design for Playing-Balls, of which the following is a specification, reference being had to the accompanying drawing, forming a part thereof.

The figure is a side elevation of a playing ball showing my new design.

I claim:

The ornamental design for a playing ball as shown.

GEORGE C. WORTHINGTON.
